UNITED STATES PATENT OFFICE.

LOUIS GRUNDIN, OF CHICAGO, ILLINOIS.

MECHANICAL STOKER.

Application filed December 20, 1920. Serial No. 431,935.

To all whom it may concern:

Be it known that I, LOUIS GRUNDIN, a citizen of the United States, residing at Chicago, in the county of Cook and State of Illinois, have invented certain new and useful Improvements in Mechanical Stokers, of which the following is a description.

My invention belongs to that general class of mechanisms known as mechanical stokers, and particularly relates to those stokers of the chain grate type.

In stokers of this type, ash and grit collect in the chain links between the pins and pin bearings, and tend to rapidly wear away the 15 pivotally interconnected members at these parts. The grates travel very slowly, not more than a few inches per minute, and as the fuel is usually wet when fed into the stocker, the water and fuel particles drip 20 through the fuel bed and collect in the pin bearings of the links. As these links pass through the hot furnace, the ash and foreign matter in the bearings become solidified or 25 caked and cause the pins to bind in the links.

My invention provides for the prevention of the accumulation of ash and other foreign matter between the pins and links bearings, and provides an outlet for the ready 30 discharge of any matter that might work into the link bearing apertures. Many other objects and advantages of the construction herein shown and described will be obvious 35 to those skilled in the art, from the disclosures herein given.

To this end my invention consists in the novel construction, arrangement and combination of parts herein shown and described, and more particularly pointed out in the 40 claims.

In the drawings, wherein like reference characters indicate like or corresponding parts,

Fig. 1 is a side elevation of one of my 45 chain grate links.

Fig. 2 is a vertical section taken on line 2—2 of Fig. 1.

Fig. 3 is a section taken on line 3—3 of 50 Fig. 1.

Fig. 4 is a side elevation of a modified 55 form of chain grate link, and

Fig. 5 is a section taken on line 5—5 of Fig. 4.

In chain grate structures there are a number 55 of links extending across the width of the combustion chamber and these links

move through the combustion chamber and discharge the ash at the rear of the chamber. 1 indicates one of the grate bar links, the same provided with a top face or fuel supporting portion 3 and a supporting web of a lesser thickness than said top and extending transversely thereto. Recesses 5 may be provided along the sides of said top and extend downwardly thereof so that the forced draft or other air supply may pass upwardly through the recesses and through the fuel bed supported by the grate.

Bearing apertures 8 extend transversely through the web adjacent its lower end, these 70 openings being preferably elongated or oblong with the long axes of the openings extending substantially parallel with the long axis of the link. The openings are surrounded by the material of the web. 75 Flanges or bosses 6 are arranged on the web each surrounding its respective opening and extending laterally of the web. Reinforcing ribs 7 may be used to connect the flanges to the fuel supporting face of the 80 link. A series of these links are arranged across the combustion chamber to form the grate and pins 2 are positioned through the openings 8.

The movement of the grate is effected by 85 sprocket wheels or the like (not shown) that engage with the pins 2. The pins 2 are adapted to engage against the outer ends of the openings resulting in forming substantially large clearance spaces 9 between the 90 inner or non-bearing side of the pin and the inner end of the opening wall. This large space between the pin and the inner side of the aperture wall tends to prevent the accumulation of all foreign matter, such as ash, therein, and in case any of such foreign matter should enter into this clearance space it would be discharged therefrom as the links pass from the roller or sprocket member.

In order to more readily provide for the discharge of ash between the pin and the opening, I have shown in Figs. 4 and 5 a modified form of flange in which the flanges 6 only partially surround their respective openings and the ends of each flange are spaced apart to form a discharge opening 10 leading obliquely downwardly from the end of the bearing aperture of the link. Thus the ash entering the bearing apertures 105 will be immediately discharged through the outlets 110.

By my improvement, the pins and links will not accumulate ash and other material therebetween, and consequently the durability of these parts will be greatly increased. Heretofore, where no provision was made for the discharge of ash between the pin and bearing aperture, the ash acted as an abrasive, and rapidly wore out these parts.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A link for a chain grate, comprising a fuel supporting portion and a supporting web; said web being formed with oblong openings surrounded by the material thereof and extending transversely therethrough, with their long axes substantially parallel with

the long axis of the link; the web being further provided with laterally extending flanges which partially surround the respective openings, the ends of each flange being spaced apart to form a discharge passage leading obliquely downward from the end of the opening.

2. A link for a chain grate, comprising a fuel supporting portion and a supporting web; said web being formed with oblong openings surrounded by the material thereof and extending transversely therethrough, with their long axes substantially parallel with the long axis of the link; the web being further provided with laterally extending flanges which partially surround the respective openings, the ends of each flange being spaced apart to form a discharge passage leading obliquely downward from the end of the opening, and reinforcing ribs connecting the flanges to the fuel supporting face of the link.

In testimony whereof I have hereunto signed my name.

LOUIS GRUNDIN.
